UNITED STATES PATENT OFFICE

102,538

DESIGN FOR AN OIL BURNER OR SIMILAR ARTICLE

Roland E. Wilcox, Chicago, and Merton Wilcox,
Palatine, Ill.

Application September 30, 1936, Serial No. 65,096

Term of patent 14 years

To all whom it may concern:

Be it known that we, Roland E. Wilcox and Merton Wilcox, both citizens of the United States, and residents, respectively, of the city of Chicago and the village of Palatine, in the county of Cook and State of Illinois, have jointly invented a new, original, and ornamental Design for an Oil Burner or Similar Article, of which the following is the specification, reference being had to the accompanying drawing, forming a part thereof.

On the drawing:

Figure 1 is a side elevational view of an oil burner heater or similar article, showing our new design, and

We claim:

The ornamental design for an oil burner or similar article, substantially as shown.

ROLAND E. WILCOX,
MERTON WILCOX.
